UNITED STATES PATENT OFFICE.

CHARLES FAYER, OF NEW YORK, N. Y., ASSIGNOR TO WAPPLER ELECTRIC COMPANY, INC., A CORPORATION OF NEW YORK.

POLARITY-INDICATING MECHANISM FOR X-RAY APPARATUS.

1,266,931.

Specification of Letters Patent. Patented May 21, 1918.

Application filed May 18, 1916. Serial No. 88,435.

To all whom it may concern:

Be it known that I, CHARLES FAYER, a citizen of the United States, residing in the city of New York, borough of Bronx, in the county of Bronx and State of New York, have invented new and useful Improvements in Polarity-Indicating Mechanisms for X-Ray Apparatus, of which the following is a full, clear, and exact description.

10 My invention relates to X-ray apparatus in which a high potential current discharge is sent through an X-ray vacuum tube, and in which the said discharge, owing to the manner of its production, may tend to follow either of two directions, whereas for safety of the tube the discharge when sent through it must always follow, relatively to the tube, the same direction.

20 My invention enables the operator, by merely reading an indicator at any time, and particularly at the moment before the commencement of the high potential current discharge through the X-ray tube, to determine which of two directions through the 25 tube the discharge tends to follow.

My invention also enables the operator, after reading the indicator as just mentioned, to instantly control the discharge circuit so as to reverse the direction the discharge tends to take, and thus prevent disaster to the X-ray tube when the discharge passes through it.

My device is of peculiar service where the discharges are made from currents supplied by a transformer and controlled by a rectifying disk rotated by a synchronous motor, this motor being driven by alternating currents from the circuit feeding the transformer. Such mechanism is shown, for 40 example, in Patent No. 992,302, dated May 16, 1911, to Reinhold H. Wappler.

Very often in such apparatus there is a rectifying disk carrying two commutator sectors, and driven at, say, 1800 revolutions per minute by a single-phase synchronous motor. Here the currents delivered by the rectifying disk may have either of two directions, for the reason that under different starting conditions the rectifying disk may occupy either of two different angular positions at the precise moment when the field of the motor is energized by current flowing through it in a given direction.

When my invention is used with apparatus

of the type just mentioned the operator, after 55 reading the indicator as above described, may if necessary reverse the direction in which the discharge is taking place, or in which it tends to take place, as the case may be.

60 My invention consists of various parts and combinations of mechanism, for attaining the particular objects above mentioned and others, all tending toward improvement in the general efficiency of the apparatus.

65 Reference is made to the accompanying drawings forming a part of this specification, and in which like letters indicate like parts in all of the figures.

70 Figure 1 is a diagrammatic perspective showing my improved indicating mechanism as used upon an X-ray machine.

75 Fig. 2 is a fragmentary diagram of certain revoluble parts shown at the left of Fig. 2, but occupying positions different from those indicated therein.

80 Fig. 3 is a fragmentary diagram of the parts shown in Fig. 2, but showing the same as moved into different positions from those indicated in said Fig. 2.

85 Fig. 4 is still another view of the parts appearing in Fig. 2, but showing them as shifted still further and into different positions.

Fig. 5 is a graphic representation of the 85 potential variations taking place in the indicator circuit as controlled by the commutator mechanism.

Fig. 6 is a longitudinal section through the armature of the synchronous motor, and 90 parts carried by such armature.

Fig. 7 is a side elevation of the synchronous motor and rectifying disk, together with my improved commutating mechanism for controlling the indicator circuit.

95 Fig. 8 is a fragmentary end elevation of the mechanism shown in Fig. 7.

Fig. 9 is a view, partly in elevation and partly in section, of my improved commutator ring forming part of the mechanism 100 for controlling the indicator circuit.

Fig. 10 is a section on the line 10—10 of Fig. 9, looking in the direction of the arrows.

105 Fig. 11 is a sectional view of a commutator brush and a plate for supporting the same, these being parts of the mechanism for controlling the indicator circuit.

6 A pair of alternating current mains are shown at 12, 13, and at 14 is a high-potential transformer the primary winding 15 of which is bridged across the mains by wires 16, 17. A hand switch 18 may be used if desired, for throwing the transformer into and out of action.

10 The secondary winding of the transformer appears at 19, and from it wires 20, 21, lead to brushes 22, 23.

15 Adjacent these two brushes is a rectifying disk 24, preferably of micanite, adapted to make 1800 revolutions per minute. Two other brushes appear at 25, 26, and from the brush 26 a wire 27 leads to a spark terminal 28. A wire 29 leads from the brush 25 to another spark terminal 30. The X-ray tube (not shown) is placed between the terminals 28, 30. The disk 24 carries a pair of commutator sectors 31, 32 which are engaged by the brushes as the disk is rotated. The brushes are mounted upon a board 33.

20 The disk 24 is secured rigidly upon a shaft 34, which is the armature shaft of a motor 35. This is a synchronous motor—of the type sometimes designated as a Tesla motor—and in this instance is of single phase. It has a rotor armature 36, a starting field 37 and a running field 38, these parts being of the usual or any desired construction. The running field is, by wires 39, 40, bridged across the mains 12, 13, and the field 37 is connected to the field 38. A hand switch 42, connected with the wire 40, is used for opening the circuit through the field 38. A wire 41 leads from the field 37 to a button switch 42, and from the latter a wire 43 leads to the wire 39. The button switch 42 is normally open, so that normally the running field 38 alone is in circuit with the mains. When the button switch is closed, however, both the starting field 37 and the running field 38, in parallel with each other, are in circuit. As a result the closing of the button switch 42 disturbs the distribution of the magnetic field relatively to the armature, and causes the wave to skip one step. I find that in practice each time the button switch 42 is closed, even for an instant, the armature, and with it the rectifying disk, is retarded or set back ninety degrees. This retardation causes a reversal in the direction of the rectified currents being delivered, or to be delivered, as the case may be, from the rectifying disk to the spark terminals.

60 The use of the button switch 42 is merely illustrative of one way in which the field polarity may be reversed. If desired the field polarity may be reversed in any other suitable manner.

65 Mounted upon the armature shaft and revoluble therewith, but spaced concentrically therefrom as hereinafter described, are a pair of metallic sectors 44, 45, separated by

sector blocks 46, 47 of insulating material. A pair of brushes 48, 49 engage the sectors 45, and are spaced angularly apart, in the direction of rotation of the sectors, by ninety degrees. A wire 50 extends from the brush 45 to an indicator 51 of a type suitable for determining the direction of a current through it, and for this purpose is provided with a pointer 52. The indicator is further provided with a resistance coil 53 for protecting it and preventing it from short-circuiting the mains. This indicator may be of ordinary construction. It is connected by a wire 54 with the main 12. A wire 55 extends from the brush 48 to the main 13.

70 The forms of various mechanical parts may be understood from Figs. 6 to 11 inclusive.

75 The motor 35 rests upon any appropriate support 56 and in this instance is provided with a spider 57 forming a part of the motor casing. Detachably secured upon this spider by fastenings 58 are two disks 59 of insulating material. Each disk 59 carries a brush holder 60, having the form of a tube bent to an obtuse angle and containing a spring 61 for pressing against the brush, 48 or 49. Each brush holder also carries a binding post 62.

80 For convenience in mounting the sectors 44, 45 and sector blocks 46, 47, I secure a metallic ring 63 upon the armature 36, and place a ring 64 of fiber or other insulating material upon the metallic ring, as shown in Figs. 9 and 10. Next the sectors 44, 45 and sector blocks 46, 47 are placed upon the ring 64, and clamped in place by a second ring 65 of insulating material. Screws 66 extend through screw holes in the rings and through bushings 67 of insulating material, the latter extending through the sectors 44, 45. The parts are thus held securely together, and in practice may be together treated as a composite ring to be mounted upon the 95 armature.

100 The graph shown in Fig. 5 represents the potential variations taking place in the indicator circuit. By considering these potential variations in connection with the action 105 of the commutator mechanism consisting of the brushes 48, 49, and sectors 44, 45, as hereinafter explained, it may be seen how the indicator is controlled for purposes of disclosing the tendency of the discharge circuit.

110 The operation of my device is as follows:

115 The various parts being assembled and arranged, I will suppose that at the start the apparatus has the condition indicated 120 in Fig. 1. The hand switch 18 is here closed, and the button switch 42 is open. A high potential discharge is now passing from the terminal 30 to the terminal 28; and the pointer 52 is in its position toward the right 125 130

of the indicator, where it indicates that the direction of the spark discharge is, say, from right to left, according to this figure.

The various circuits may be readily traced.

- 5 The primary circuit is as follows: main 12, wire 16, primary winding 15, wire 17, hand switch 18, main 13 to alternating current generator (not shown), thence to main 12.
- 10 A secondary circuit, of momentary duration, may be traced as follows: secondary winding 19, wire 20, brush 22, sector 31, brush 25, wire 29, terminal 30, thence across the spark gap (or through the X-ray tube) 15 to the terminal 28, wire 27, brush 26, sector 32, brush 23 and wire 21, back to secondary winding 19.

- The field circuit is as follows: main 12, wire 39, running field 38, wire 40 to main 20 13, thence to alternating generator (not shown) and back to main 12.

- The indicator circuit, which remains unchanged for a moment only, is as follows: main 12, wire 54, indicator 51, with its resistance winding 53, wire 50, brush 49, sector 45, brush 48, wire 55, main 13 to alternating generator (not shown) and thence to main 12. The indicator is for the moment subjected to the maximum voltage of the line 30 current, in the direction in which it for the moment is flowing. Thus the voltage affecting the indicator is represented at the curve marked + and disposed at the left of Fig. 5, and the pointer 52 remains steadfast 35 in the position in which it is shown.

- The next step in the automatic action of the apparatus is a reversal in the direction of the current energizing the mains 12, 13, and this reversal of the current mentioned 40 is accompanied by a rotation of ninety degrees in the armature shaft and all parts carries thereby, in a clockwise direction according to Fig. 1, so that the parts thus rotated now appear as indicated in Fig. 2. 45 This brings about some changes in the circuits.

- The circuit through the primary winding 15 of the transformer 14 is the same as above traced, but the direction of the current through the primary winding is now momentarily reversed.

- A secondary circuit, of momentary duration only, may be traced as follows: secondary winding 19, wire 21, brush 23, sector 31 5 (see Fig. 2), brush 25, wire 29, terminal 30, X-ray tube (not shown), terminal 28, wire 27, brush 26, sector 32 (see Fig. 2) brush 22, and wire 20 back to secondary winding 19. The high potential discharge, forming a part of the circuit just traced, has now the same direction as at the start, because although the induced current from the secondary winding 19 has now a reversed direction relatively to the winding, its direction for purposes of the terminals 30 and 28 is

rectified by the change in position of the sectors 31, 32. In other words, the direction of the high potential discharge through the X-ray tube is rendered normal by the action of the rectifying disk.

The indicator circuit, however, is now open as the sector 44 engages the brush 48 and the sector 45 engages the brush 49, there being no conductive connection from one sector to the other. If the current could now flow through the indicator its direction would be reversed relatively to its direction of flow according to Fig. 3, and hence would be graphically represented by the second curve, marked —, and disposed below the median line in Fig. 5. This fact is here pointed out merely as a means of bearing in mind the changing phase relations of the various movable parts. No current now passing through the indicator, or at least 85 the indicator not now being subjected to the maximum voltage, the pointer 52 still remains in its position at the right. The action of the mechanism as a whole being continued, another reversal in the direction 90 of the current through the mains, accompanied by a further rotation of ninety degrees by the armature, causes the armature to occupy the position indicated in Fig. 3. This movement brings the sector 32 into the 95 position originally occupied by the sector 31, and also brings the sector 45 into the position originally occupied by the sector 44. These changes, together with the fact that the flow of the primary current is now in 100 the same direction as in the beginning, brings the entire apparatus into a condition substantially identical with that disclosed in Fig. 1. Therefore the discharge between the terminals 30 and 28 is in the same direction as before; current now flows through the indicator in the same direction as in Fig. 1, this current having the maximum voltage of the mains, and hence being graphically represented in Fig. 5 by the 105 third curve from the left thereof, marked +. The pointer 52 therefore still remains steadfast in its original position indicated in Fig. 1.

The action of the mechanism being continued still further the armature assumes the position indicated in Fig. 4, which is closely analogous to that indicated in Fig. 2, and for purposes of all electrical results may be considered as identical therewith.

Therefore the indicator circuit is open, the pointer 52 still remains in its extreme position at the right, as shown, and the conditions of the voltage and current which would obtain in this circuit if closed are shown 125 graphically by the curve at the extreme right, marked —, in Fig. 5.

So long as the button switch remains undisturbed, the high potential discharges all have the same direction, and the pointer 52 130

remains in a fixed position associated with such direction.

Suppose, next, that the mechanism is in the condition shown in Fig. 1, and that the operator momentarily closes the button switch. This completes a circuit as follows: Main 12, wire 39 whence the current divides, a part passing to the field 38 and a part passing through the wire 43, button switch 42 and wire 41 to the field 37, the two portions of the current thence uniting, wire 40, main 13 to alternating generator (not shown) to main 12. This circuit energizes the two fields 37, 38 in parallel, and by so doing 70 disturbs the distribution of the magnetic field and the magnetic torque thereof. The button switch after being closed momentarily is opened immediately so that the field 37 is deenergized, the original condition of the 75 magnetic torque is restored, and the armature after being thrown out of step is again brought into step, but as no corresponding change is made in the phases of the line current the armature is retarded, or displaced angularly backward as compared 80 with the position it would otherwise occupy, by exactly one quarter of a revolution as above explained.

Since, therefore, the armature normally 85 makes one complete revolution while the current in the mains 12, 13 makes four reversals or two complete cycles, the above-described angular displacement of the armature has relatively the same effect as a reversal in direction of the current flowing 90 in the mains 12, 13, without any corresponding change in the position of the armature.

For convenience in further tracing the circuits I will again refer to Fig. 1, and will consider that owing to a momentary closure of the button switch 42 the direction of flow of current in the mains 12, 13 is now reversed, without any corresponding change being made in the position of the armature and rectifying disk.

The primary circuit, unchanged except as to direction of the flow of current, is as follows: main 13, switch 18, wire 17, primary winding 15, wire 16, main 12, to dynamo 95 (not shown), thence back to main 13.

A secondary circuit, of momentary duration, may be traced as follows: secondary winding 19, wire 21, brush 23, sector 32, brush 26, wire 27, terminal 28, X-ray tube 100 (not shown), terminal 30, wire 29, brush 25, sector 31, brush 22, and wire 20, back to primary winding 19. This circuit causes a high potential current discharge to take place through the X-ray tube in the direction 105 from the terminal 28 to the terminal 30—that is, in the direction contrary to the one first contemplated.

Further rotation of the armature shaft 110 will bring the rectifying disk successively into the positions indicated in Figs. 2, 3 and

4, and the circuits will be the same as above traced with reference to these figures, though in each instance the current will be in the contrary direction to the one previously contemplated. Hence all of the high potential 115 current discharges now pass from left to right, from the terminal 28 through the X-ray tube to the terminal 30.

Referring again to Fig. 1 and bearing in mind the reversal in the flow of current 120 through the mains 12, 13, due to the momentary closure of the button switch 42 above mentioned, the field circuit is as follows: main 13, wire 40, running field 38, wire 39 to alternating generator, thence to main 12.

The indicator circuit, which remains unchanged for a moment only, is as follows: main 13, wire 55, brush 58, sector 45, wire 50, indicator 51, wire 54, main 12, dynamo (not shown) and main 13. Since the current 125 in the mains is now for the moment flowing in a direction contrary to the one first contemplated, the indicator is affected accordingly and the pointer 52 swings to the left and takes up the new position indicated by dotted lines.

As the armature continues its rotation, so 130 that the various revoluble parts assume progressively different positions as indicated in Figs. 2, 3 and 4, the alternations of the current through the mains 12, 13 are of course accompanied by rectifications of the high potential current discharges, due to the ordinary work of the rectifying disk, and the indicator will persistently register the same 140 indication so long as no further change is brought about.

Each time the button switch is closed and opened, therefore, the direction of the high potential current discharge is reversed, and 145 a corresponding indication is made and persistently registered by the indicator—the deflection of the pointer in one of two directions being a guide for disclosing the direction in which the high potential current 150 discharge tends to take place.

By the use of my apparatus the operator 155 can readily avoid the danger of exposing valuable X-ray tubes to the action of high potential current discharges flowing in the wrong direction.

In practice the operator places the X-ray tube in position, starts the motor into action and makes his reading of the indicator before he allows the high potential current 160 discharges to take place through the tube.

He can control time of the high potential 165 discharges by throwing the transformer into and out of action by use of the hand switch 18 or in any other desired manner.

My device can be used to advantage as an attachment for X-ray machines, but if preferred it can be permanently incorporated 170 in the machine.

I do not limit myself to the precise con- 175

struction shown, as variations may be made therefrom without departing from the spirit of my invention.

I claim:—

- 5 1. In an apparatus of the character described the combination of alternating current mains, a step-up transformer connected with said mains and thereby energized, a rectifying switch connected with said transformer and energized thereby for delivering high potential discharges of unitary but uncertain direction, a synchronous motor connected with said alternating current mains and energized thereby for actuating said rectifying switch, means for indicating the direction of said high potential discharges, and mechanism controllable at the will of the operator for momentarily retarding the speed of said synchronous motor relatively 40 to the frequency of the phasal changes in said alternating current mains.
- 10 2. In an apparatus of the character described the combination of a pair of alternating current mains, a primary circuit bridged across said mains and adapted to be energized thereby, a secondary circuit inductively coupled to said primary circuit and energized thereby for producing high potential current discharges, rectifying mechanism connected with said secondary circuit in order to rectify said discharges, a synchronous motor, said motor being connected with said rectifying mechanism in order to actuate the latter, a commutator 45 driven by said motor and connected with said alternating current mains by a circuit bridged across said mains independently of
- 15 said primary circuit, for selectively diverting from said alternating mains currents of unitary direction, an indicator electrically connected to said commutator in order to indicate the direction of said currents, and means controllable at the will of the operator for momentarily retarding the action of the motor as related to the time of the current phase in the alternating current mains. 45
- 20 3. In an apparatus of the character described the combination of a pair of alternating current mains, a transformer connected with said mains and energized thereby for producing high potential discharges, a rectifying switch connected to said transformer and coacting therewith to render the discharges of unitary but uncertain direction, a synchronous motor connected with said alternating current mains and energized thereby, a revolute shaft connected with said motor and with said rectifying switch for enabling said rectifying switch to be driven, a commutator carried by said revolute 50 shaft, a circuit bridged across said alternating current mains independently of the connection of said motor to said mains, said circuit being connected with said commutator and controllable thereby for selectively diverting currents of unitary but uncertain direction from said mains, an indicator for disclosing the direction of flow of said currents, and means controllable at the will of the operator for momentarily retarding the 55 speed of said motor relatively to the frequency of the phasal changes in said alternating current mains. 60
- 25 4. In an apparatus of the character described the combination of a pair of alternating current mains, a primary circuit bridged across said mains and adapted to be energized thereby, a secondary circuit inductively coupled to said primary circuit and energized thereby for producing high potential current discharges, rectifying mechanism connected with said secondary circuit in order to rectify said discharges, a synchronous motor, said motor being connected with said rectifying mechanism in order to actuate the latter, a commutator 65 driven by said motor and connected with said alternating current mains by a circuit bridged across said mains independently of
- 30 said primary circuit, for selectively diverting from said alternating mains currents of unitary direction, an indicator electrically connected to said commutator in order to indicate the direction of said currents, and means controllable at the will of the operator for momentarily retarding the action of the motor as related to the time of the current phase in the alternating current mains. 70
- 35 5. In an apparatus of the character described the combination of a pair of alternating current mains, a primary circuit bridged across said mains and adapted to be energized thereby, a secondary circuit inductively coupled to said primary circuit and energized thereby for producing high potential current discharges, rectifying mechanism connected with said secondary circuit in order to rectify said discharges, a synchronous motor, said motor being connected with said rectifying mechanism in order to actuate the latter, a commutator driven by said motor and connected with said alternating current mains by a circuit bridged across said mains independently of

CHARLES FAYER.
